CARRIER FOR LAUNDRY ASSORTING MACHINES

Angus F. Hanney, Norwood, Ohio, assignor to The American Laundry Machinery Company, Cincinnati, Ohio, a corporation of Ohio

Application November 3, 1932, Serial No. 641,110

6 Claims. (Cl. 105—154)

This invention relates to carriers such as are employed in laundry assorting mechanisms wherein pieces of work, to which laundry identification clips have been secured, are to be conveyed from one station to another. Conveyance is had by movement of the carrier along a rail, by engagement of the carrier with a chain moving adjacent the rail, the carrier supporting the clip and thus conveying the piece 10 of work to which the latter is attached.

Such an apparatus is fully illustrated and described in my copending application for Laundry assorting mechanism, Serial No. 641,109, filed of even date herewith, from which it will be observed that the apparatus includes a large 15 number of carriers.

The object of this invention is to provide a carrier of improved form and one adapted to be cheaply manufactured, as of sheet metal, in 20 the quantities necessary.

The exact nature of this invention, together with further objects and advantages thereof will be apparent from the following description taken in connection with the accompanying 25 drawing, in which Fig. 1 is a perspective view of a carrier embodying the invention, shown in upright or carrying position, parts being broken away to show details of construction; Fig. 2 is a perspective view of the same in inverted 30 position as when being returned from the delivery end of the apparatus; Fig. 3 is a development illustrating the blank of sheet metal from which the carrier is made; Fig. 4 is a typical section transverse of a return stretch of conveying apparatus, showing the carrier in inverted 35 position upon its rail, together with the associated actuating chain; and Fig. 5 is a typical section transverse of a delivery stretch of the conveying apparatus, showing a laundry identification clip supported in the carrier, and the latter supported in upright position on its rail.

With reference now to the drawing, the principal parts of the carrier are a rail receiving part, generally of U-form, and a box part at the base of the U, and adapted to receive and retain the laundry identification clip. The entire device is made from a sheet metal blank as indicated, Fig. 3, bent and otherwise deformed 50 as indicated by the broken lines in that figure.

More specifically, the rail receiving U part has a rectangular base panel 1, this being the central panel of the blank, at the ends of which are a pair of upstanding side members 2. The 55 angles between these three members are rein-

forced by the deformations 3. The side members 2 are deformed at their ends as indicated to provide a pair of inwardly extending lugs 4. These lugs are hollow, flat on top, of semi-circular contour and have cylindrical faces 5, all as illustrated in the drawing.

The box part of the device includes as its top panel the base panel 1 of the U. It has sides 6 extending from the panel 1 in the opposite direction from the side members 2 of the U. The bottom of the box part is provided by a pair of flanges 7 extending toward each other from the free extremities of the sides 6 and leaving therebetween a slot 8. One end of the box part is open and the flanges 7 are chamfered as at 9 15 at that end to provide a mouth for the slot 8. The opposite end of the box part is closed by a flap 10 extending from one of the side panels 6, with a tab 11 at its end which is bent around the opposite side panel 6 and into a shallow 20 recess 12 provided therefor. The angles between the panels 1 and 6 are reinforced by deformations 13 similar to but smaller than the deformations 3.

The blank is cut as at 14 to provide a finger 25 15 upstanding from the panel 1 at one side thereof, into the space within the U between the side members 2.

With reference now to Fig. 5 in which a rail member A appears in transverse section as suspended from a bracket B, it will be noted that the carrier will ride upon the rail with its U part embracing the rail and its lugs 4 resting upon the top thereof, the curved faces 5 of the lugs bearing upon the top rail surface. Thus 30 35 the carrier is free to tilt in the plane of the rail, and though the rail have sufficient slope that the carrier will be caused to slide therealong by gravity, the carrier will, nevertheless, remain substantially vertically positioned. 40

In Fig. 5 the carrier is shown supporting a laundry identification clip C. The clip has a head part within the hollow of the box part of the carrier, and is engaged in the slot 8 of the carrier because of the widened mouth of the slot, and the clip being positioned along the slot by its bearing against the end closure 10. 45

In Fig. 4 the carrier is shown in inverted position, resting upon the rail A which is likewise 50 inverted and supported as by the bracket D. It is now the panel 1 which bears upon the rail, removal of the carrier from the rail being prevented, however, by the lugs 4. A chain E arranged to travel along the rail will be noted 55

as engaging the finger 15 of the carrier by which the carrier is caused to travel, as along an upwardly extending stretch of the rail.

What I claim is:

5. 1. A carrier for the purpose described comprising a rail-receiving part of U-form with rail-engaging lugs inwardly extending from the ends of the U side members, and a box part at the base of the U with an open end and a down-
wardly-opening slot leading therefrom, to receive and retain a laundry identification clip.
- 10 2. A carrier for the purpose described, of sheet metal, bent to provide a rail-receiving part of U-form, with rail-engaging lugs inwardly extending from the ends of the U side members, a box part at the base of the U with an open end and slotted bottom to receive and retain a laundry identification clip, and having a finger extending within the U for engagement with actuating means to cause the device to travel along the rail.
- 15 3. A carrier for the purpose described, of sheet metal, bent to provide a rail-receiving part of U-form, with rail-engaging lugs inwardly extending from the ends of the U side members, a box part at the base of the U with an open end and slotted bottom to receive and retain a laundry identification clip, and having a finger extending from said box part within the U for engagement with actuating means to cause the device to travel along the rail.
- 20 4. A carrier for the purpose described, of sheet metal, bent to provide a box part having an open end and a bottom slotted from said

end, to receive and retain a laundry identification clip, a member extending across the other end to prevent removal of said clip therethrough, members extending upwardly from the ends of said box part as in a U, lugs inwardly extending from the ends of said U side members to engage a rail received within the U, and a finger extending from said box part within the U for engagement with actuating means to cause the carrier to travel along the rail.

10 5. A carrier for the purpose described, of sheet metal, bent to provide a rail-receiving part of U-form, and a box part at the base of the U with an open end and slotted bottom to receive and retain a laundry identification clip, and deformed to provide rail-engaging lugs inwardly extending from the ends of the U side members, with curved bottom surfaces to permit rocking of the carrier in the plane of the rail.

15 6. A carrier for the purpose described, of sheet metal, bent to provide a rail-receiving part of U-form, with rail-engaging lugs inwardly extending from the ends of the U side members, a box part at the base of the U with an open end and slotted bottom to receive and retain a laundry identification clip, and having a finger extending within the U for engagement with actuating means to cause the device to travel along the rail, said lugs being formed with curved bottom rail-engaging surfaces to permit tilting of the device upon the rail as upon said on a slope.
